CASING SPINNING APPARATUS FOR DRILLING RIGS

Filed Feb. 1, 1929

FIG. 1.

FIG. 2. FIG. 3.

UNITED STATES PATENT OFFICE

WALTER W. FOSTER, OF WICHITA FALLS, TEXAS

CASING SPINNING APPARATUS FOR DRILLING RIGS

Application filed February 1, 1929. Serial No. 336,812.

This invention relates to well drilling equipment and it has particular reference to a combination of elements designed to co-operate in setting up well casing and the principal object of the invention resides in the provision of apparatus receiving its power of operation from the draw works line shaft of the conventional rotary drilling equipment, and capable of reducing to the very minimum manual labor, accidents and cost of operation incident to the operation of setting up casing in the old and established manner, that of operating a line off the constantly rotating cat head affixed to the line shaft.

Still further, the invention comprehends the provision of apparatus as set forth including as its foremost elements a weighted element for returning the lines to operative position after each operation, and a yieldable sheave so arranged as to relieve any strain upon the parts and especially the casing joints in event the latter is improperly engaged by the casing sections as the latter are placed in position for threading in, which fact frequently results in damaging the threads of either the joint or casing section in the absence of means to prevent, as provided by the invention.

Yet another object of the invention resides in the provision of apparatus as specified for simple, economical and durable nature and requiring little skill in operation and so designed as to be used both in the operation of setting up and breaking out casing and tubing sections, by simply interchanging the lines in order that they may be either entwined about the casing being threaded in or to the end of the tongs in breaking joints.

With the foregoing objects as paramount, the invention has particular reference to its salient features of construction and arrangement of parts by which the foregoing objects are attained, and which will become manifest as the description proceeds, taken in connection with the accompanying drawings wherein:—

Figure 1 represents a fragmentary view of a derrick, showing the drawworks, friction

hoist and line assembly and its connection with the casing line.

Figure 2 is a detail view of the counter balance with portions cut away to illustrate the guide line therethrough.

Figure 3 is a detail view of the draw line sheave showing the yielding frame supporting the same, and

Figure 4 is a sectional view of one of the derrick legs, showing the pulleys near the derrick floor and under which the lines pass and are operatively directed toward the casing assembly or tongs, as the case may be.

Continuing now more in detail, the derrick is indicated by the character 1, and the leg 65 upon which the elements of the invention are mounted is specifically indicated at 2.

The conventional draw works, generally referred to at 3 in Figure 1, is positioned relative to the rotary table 4, shown incomplete also in Figure 1, has the conventional line shaft 5 and drilling drum 6, but which latter has no operative relationship with the present invention.

Situated upon the line shaft 5 in the place of the conventional cat head, but forming the subject matter of a separate application for Letters Patent, is a friction hoist comprised of a special cat head 7 having a flange 8, the latter being provided with a friction periphery. Below this cat head is situated a friction wheel, the flange 9 of which is aligned with the friction surface of the flange 8 of the special cat head. This friction wheel is arranged upon a special mounting, and secured to the jack post 10, by means of the bolts used in securing the journal box 11 to the jack post, and the mounting is so arranged as to provide a spindle 12 off centered with respect to the rotating axis of the wheel, which latter is indicated at 13. This feature enables the wheel 9 to be oscillated to bring its periphery into engagement with that of said cat head flange 8 in order that the rotating motion of the latter will be imparted to the friction wheel 9. Oscillation of this friction wheel in the manner above described is attained by pressure upon the operating lever 14 extending to an accessible position near the derrick floor.

Affixed to rotate with the friction wheel 9, which latter is normally idle, is a drum 15, about which is wound a line 16, the latter extending upwardly and over a sheave 17 suspended in a suitable frame, to be described later, and downward and affixed in an eye 18 secured to the weight 19.

With particular reference to this weight 19, shown in detail in Figure 2, it will be observed that a longitudinal opening 20 is made therein parallel with respect to its line of travel, through this opening is passed a line 21, which latter is connected to a bracket 22, near the sheave 17, the opposite end being connected to a mounting 23, near the lower end of the derrick leg 2, and which latter mounting serves to support pulleys 24 and 25 and will be later referred to. The line 21 passing through the weight 19 serves as a guide for the latter, constraining the same to travel near the leg of the derrick and thus be out of the way of the operators. It will likewise be noted that near the upper securing point of this line is incorporated a turn buckle 26, by means of which the line may be tightened when it becomes slack, in order that as little friction as possible will be present during reciprocative movement of the weight thereon.

To the bottom of the weight 19 is affixed preferably two eyes 27 as shown in Figure 1, and while one eye may be sufficient, two have been shown to accommodate two lines, although these lines are alternately used as will become apparent presently.

In spinning in casing sections, a line 28 is affixed to one of the eyes 27, and is threaded under pulley 24 or 25 and the other end thereof wrapped, in the manner shown in Figure 1 about the joint of pipe protruding from the well, preparatory to slipping the same upward upon the lower end of the casing section 29, as it is lowered by the elevator, (not shown) to seat upon the joint. When seated, the loosely wrapped line is manually slipped upward, upon the casing section 29, whereupon one operator holds the free end of the line 29, while another operator depresses the treadle at the end of lever 14, which action causes the friction wheel 9 to move against the friction surface of the cat head flange 8, which, it will be understood is constantly rotating. Obviously, the line 16 begins to wind upon the drum 15, carried by the friction wheel 9, causing the weight 19 to ascend, pulling with it the end of the line 28, and thus turning the casing section 29 suspended by the elevator above the joint.

Frequently, the end of the suspended section is improperly seated in the joint, and with the old methods of spinning in, the strain upon the line is positive and has no provisions for yieldability. Therefore, should the section be improperly seated, either the joint or section is likely to be shorn

of threads, or other equally disastrous results, requiring that another joint or section be substituted. To avoid such a condition, the present invention affords a means in the form of an inverted U shaped frame 30, between the legs of which is interposed the sheave 17 over which the line 16 is passed, and above the sheave is a compression spring 31, and a lateral element 31a integral with the frame 30, through which passes a rod 32, freely slidable through the top of the U shaped frame 30. At the lower end of the rod is a washer 33, below which is a nut 34 which abuts the lateral element 31a when weight is applied to the sheave 17. The spring is of considerable strength, capable of supporting a maximum load of approximately six or seven thousand pounds, and obviously when a load of such proportion is imposed upon the sheave 17, the spring 31 is compressed, thus alleviating any sudden strain upon the joint in the manner described above. The washer 35 and retaining nut 36 are arranged to limit the compression and extension of the spring 31.

The invention of course anticipates the use of any type of means for yieldingly suspending the overhead sheave 17, whether it be of the character shown and described or its equivalent that shown being merely the preferred structure.

As mentioned previously, the apparatus may be used for setting up casing, that is to say, spinning in by means of a line on tightening the joint by connecting the line to the end of the tongs and imparting thereto a series of oscillatory movements until the joint is secure. In the latter case, tongs are employed, and in the absence of apparatus such as provided by the invention, this work must be done manually. It is necessary only to disconnect the line 28 from the eye 27, connect a shorter, and possibly a wire instead of a manila line to the eye, thread it through one of the pulleys below the weight and connect the free end to the handle of the tongs (not shown). As the lever 14 is actuated to engage the friction elements, the tongs are actuated to rotate the casing section to tighten it into the joint. A suitable spring or weight may be used to return the tongs to a new position for operation, which function is an established and well known process.

It is apparent from the foregoing that the operation of spinning in and setting up casing, tubing and the like, heretofore considered a difficult and distasteful task has been rendered by the invention a comparatively easy operation, and one in which there is little likelihood of mishap such as entangling an operator in the lines, which, as apparent, are well out of the way, or other accidents common to the carrying out of the operations aforesaid.

It is understood however, that while the invention has been described in detail, modifi-

cations and changes are possible from time to time as are considered within the scope and meaning of the following claims.

What is claimed is:—

- 5 1. In an apparatus of the type set forth, pulling means, a line connected at one end to said pulling means to be pulled thereby and having its opposite end vertically disposed, a weight connected to said vertically disposed end, and a second line connected to the weight at one end and having its other end free and adapted to engage about and rotate a casing.
- 10 2. In an apparatus of the type set forth, pulling means, a line connected to said pulling means to be pulled thereby and extending vertically both upwardly and then downwardly, a line for engaging about a casing to rotate same, and means interposed between the downwardly extending part of the first line and the second line and connected to each to restore same to normal position after each operation thereof.
- 15 3. An apparatus for spinning in and setting up casing sections and the like including a line for having operative connections to said casing, a second line connected to said first line, means to impart a pull upon the opposite end of the second line to impart to said 20 casing section a series of rapid rotary movements, means to allow said second line to yield to the pull imparted thereto and means to return said lines to original position after each operation.
- 25 35 In testimony whereof I affix my signature.
WALTER W. FOSTER.
